SURGICAL FRACTURE APPARATUS

Glenn J. Baker, Jr., Los Angeles, Calif.

Application December 31, 1942, Serial No. 470,847

1 Claim. (Cl. 128—85)

This invention relates to surgical fracture apparatus, and has more particular reference to an improved splint for use in placing a patient's limbs under proper tension and maintaining the same under such tension, so that the adjacent ends of the broken bone of the limb will remain in proper relation after being set and during the period that the bone is knitting.

The primary object of the present invention is to provide a splint of the above kind which is extremely simple and durable in construction, highly reliable and efficient in use, and so constituted as to insure maximum comfort to the patient.

Other objects and features of the invention will become apparent from the following description when considered in connection with the accompanying drawings, and the invention consists in the novel form, combination and arrangement of parts hereinafter more fully described, shown in the drawings and claimed.

In the drawings:

Figure 1 is a side elevational view of the splint constructed in accordance with the present invention, and illustrating the same applied to a patient's arm.

Figure 2 is a top plan view of the construction shown in Figure 1.

Figure 3 is an enlarged transverse section taken on line 3—3 of Figure 2.

Figure 4 is an enlarged fragmentary transverse section taken on line 4—4 of Figure 2.

Figure 5 is an enlarged plan view of one section of one of the adjustable limb supporting straps forming part of the apparatus shown in Figure 1.

Figure 6 is a view similar to Figure 5 of the other or cooperating section of said supporting straps.

Referring in detail to the drawings, the present fracture splint consists of an elongated frame preferably composed of an inner section A and an outer section B. The inner frame section A consists of a pair of side members or bars 5 arranged in slightly outwardly or forwardly converging relation and rigidly connected at their inner ends by means of a downwardly directed arcuate limb clamping member 6 having a suitable pad covering 7. Connecting the inner end portions of the side bars 5 of inner frame section A is a clamping or securing strap composed of adjustably connected sections 8 and 9. The clamping member 6 is adapted to pass under the limb at the inner or upper portion of the latter, and the clamping strap 8, 9 is adapted to pass outwardly about or over the limb so as to cooperate with the member 6 for securely clamping or se-

curing the inner end of the frame to the limb. A series of bandaging straps are provided at regular spaced intervals along and connecting the side frame bars 5 so as to sustain the limb in a comfortable manner when placed in a substantially horizontal position. These straps are arranged to pass under and then over the limb and are adjustable in length to encircle the different portions of the limb. As shown, each of the bandaging straps consists of a section 10 having a loop at its inner end and a section 12 having a similar loop 12 at its inner end. The outer ends of the sections 10 and 12 are passed through the loops 11 and 12 after passing about the associated side frame bars 5 and the outer end portion of strap section 10 has a longitudinal series of apertures 13 arranged to cooperate with a buckle 14 on the outer end of the strap section 12. The loops 11 and 12a are of such a size that the outer end of section 10 may pass through said loop 11 and the buckle 14 may pass through the loop 12a in applying the strap sections to the frame bars 5.

The splint frame section B consists of a U-shaped member having tubular legs slidably receiving the outer ends of the frame bars 5 of the inner frame section A, so that the frame may be adjusted in length. Set screws 15 are carried by the legs of section B and arranged to impinge the frame bars 5 to secure the outer frame section B in adjusted relation to the inner frame section A.

A transverse cross head 16 is arranged between the legs of the outer frame section B and adjustable longitudinally of the latter, said cross head having arcuate end members 17 partially embracing the legs of section B so as to slidably mount said cross head in place. An ankle or wrist band 18 is connected with the cross head 16 by means of adjustable straps 19 that extend inwardly or rearwardly to the wrist band. As the wrist band is adjustable, it may be securely fastened about the ankle or wrist of the limb, and by adjusting the cross head 16 outwardly, the patient's limb may be placed and maintained under proper tension. Such tensioning means may consist of an adjusting screw 20 journalled in the outer intermediate portion of outer frame section B as in 21 and provided on its other end with a suitable handle or crank 22, the inner threaded stem of screw 20 having threaded engagement with the outer end portion of an open rectangular frame 23 whose inner end is apertured to slidably receive a stem 24 rigid with and projecting outwardly from the intermediate portion of cross head 16. The outer end of stem 24 has a head 25, and a compression spring 26 en-

circles the stem 24 between the inner end of frame 23 and head 25. Head 25 also has a lateral pointer 27 cooperating with graduations 28 on the adjacent side of frame 23. Thus, by turning screw 20 the frame 23 may be adjusted outwardly so as to increase the tension of spring 26 to the extent indicated by the pointer 27 in connection with graduations 28. In this way, an accurate desired tension may be placed upon the patient's limb upon which the splint is used. This tension may be secured by means of a jam nut 29 threaded on adjusting screw 20 and arranged to impinge the outer end of frame 23 when tightened.

Connecting the outer ends of the side bars 5 of the inner frame section A and depending therefrom is a U-shaped member 30 adapted to extend well below the splint frame at a point near the patient's hand or foot. Thus, the support 30 may contact the floor or any other supporting surface so as to maintain the patient's hand or heel elevated above said surface and out of contact with the latter. It will thus be seen that I have provided a very simple and durable fracture splint which is convenient to use and highly reliable and efficient in use. At the same time, the splint affords extreme comfort to the patient as well as safety against undesired contacts with a supporting surface during the period of mending or knitting of the bone of the fractured limb. The ankle or wrist band 18 is preferably provided with a soft lining or padded inner surface for obvious reasons.

What I claim as new is:

A fracture splint comprising an inner frame

section and an outer frame section, said inner frame section comprising spaced side bars and a downwardly extended arcuate member rigidly connecting the inner ends of said bars, a securing strap at the inner end of the inner frame section, 5 a series of bandaging straps adjustable in length and connecting the side bars of the inner frame section at suitable intervals so as to pass around the patient's limb, said outer frame section comprising 10 a U-shaped member having tubular legs slidably telescoped upon the outer ends of the side bars of the inner frame section, means to secure the frame sections in relatively adjusted position, a wrist or ankle band, a cross head 15 slidably longitudinally of the outer frame section, a pair of laterally spaced adjustable straps flexibly connecting the cross head to the top and bottom of said ankle or wrist band, and manually operable means to longitudinally adjust the cross head in the frame, said last named means comprising 20 an adjusting screw journailed in the outer end of the outer frame section, a rectangular frame member, said adjusting screw having threaded engagement in the outer end of said last named frame member, a stem 25 slidable through the inner end of the last named frame member and fixed to the cross head, the outer end of said stem having a head, and a compression spring encircling said stem between said head and the inner end of said last named frame member.
